(57) **CLAIM**

We claim the ornamental design for an electronic device battery door, as shown and described.

DESCRIPTION

FIG. 1 is a front perspective view of an electronic device battery door;

FIG. 2 is a back perspective view of the electronic device battery door;

FIG. 3 is a front elevational view thereof;

FIG. 4 is a back elevational view thereof;

FIG. 5 is a right elevational view thereof;

FIG. 6 is a left elevational view thereof;

FIG. 7 is a top plan view thereof; and,

FIG. 8 is a bottom plan view thereof.
